UNITED STATES PATENT OFFICE

SYLVESTER A. JOHNSON, OF NORTH PROVIDENCE, RHODE ISLAND, ASSIGNOR TO SPEIDEL BROS., OF PROVIDENCE, RHODE ISLAND, A FIRM COMPOSED OF ALBERT E. R. SPEIDEL AND EDWIN F. M. SPEIDEL

BRACELET END CONNECTER

Application filed May 9, 1930. Serial No. 451,010.

This invention relates to a bracelet end connector frequently called an "end hook", and has for its object to provide means whereby the bracelet may be adjustably connected to the connector to vary its encircling size.

A further object of the invention is to provide a construction by which the bracelet may be detachably connected to the connector.

With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a top plan view of the bracelet secured to the connecting device adapted for engagement with the lug of a wrist watch;

Fig. 2 is a bottom view thereof;

Fig. 3 is a side elevation with one link in section;

Fig. 4 is a view similar to Figure 3 with the connecting device and end link in section;

Figs. 5, 6 and 7 are views taken on line 5-5 of Figure 4 showing the link as in three different adjusted positions which it may assume in the body;

Fig. 8 is a perspective view of the body of the connector;

Fig. 9 is a perspective view of the outer surface of the pivoted member;

Fig. 10 is a perspective view of the inner surface of the pivoted member.

In the use of wrist bracelets for securing a watch to the arm of the wearer, it is desirable to provide some means for varying the length of the encircling bracelet which has been frequently accomplished by removing one of the links from the bracelet to shorten its size or adding a link to extend the encircling size of the bracelet. It is found, however, that in the use of large links that the change in size of the bracelet by the addition

or omission of one of its links does not provide an accurate enough adjustment of the bracelet about the wrist, and in order to obtain intermediate adjustments less than the length of one of the links, I have provided a pivoted member in the body of the end hook having

a plurality of fingers and also a hook at its end, any one of which may extend through the frame link to engage its end bar and hold the same in the desired position in the connecting member to vary the encircling size of the bracelet about the wrist; and the following is a detailed description of the present embodiment of this invention illustrating the preferred means by which these advantageous features may be accomplished.

With reference to the drawings, 10 designates the frame links of the bracelet suitably hingedly joined together by sheet metal connectors 11, the end link 10 being connected to the end hook which consists of a body portion 12 provided with a rolled or folded eye 13 at one end to engage the bail or lugs of a wrist watch, and which is provided at its opposite end with a hook 14, side walls 15 which extend along the sides of the body and are pierced as at 16 to receive the trunnions 17 of the securing member 18 which has fingers 19 at either of its ends and an intermediate finger 20 extending therefrom, either one of which may extend into the opening 21 of the frame link 10 and in sufficiently close proximity to the top wall of the body 12 to lock it in the end connector in adjusted position.

If the maximum length of the bracelet is desired, the frame link 10 will engage the hook 14 as illustrated in Figure 4, in which case the finger 19 adjacent the hook will close the openings 22 of the hook sufficiently to prevent removal of the link therefrom. If the bracelet is to be made shorter, the link 10 may be moved inwardly to a position to be engaged by the finger 19, as shown in Figure 5, or if still shorter adjustment is desired, it may be moved inwardly to engage the finger 20, as shown in Figure 6, or if a still shorter size is desired, it may be moved inwardly to engage the finger 19 on the opposite end of the securing member, as shown in Figure 7 to hold it in position.

It is of course obvious that any desired number of fingers may be provided depending on the length of the securing member and the length of the body of the connector. The securing member 18 may be held in locked position by the lateral extensions 23 frictionally

engaging the ears 24 on the body to prevent accidental movement of the member and detachment of the end link 10 from the hook.

While I have described certain construction forms which embody the principles of my invention, it is obvious that other desired changes in arrangement may be made within the spirit and the scope of the invention as defined in the appended claims.

10 I claim:

1. A device for connecting a link bracelet to a wrist watch comprising a body member having side walls and means at one end to engage the lugs of a wrist watch, a member movably mounted between said side walls and provided with a plurality of spaced fingers, any one of which may extend into the opening in a link positioned in said body to adjustably secure it thereto.

20 2. A device for connecting a link bracelet to a wrist watch comprising a body member having side walls and means at one end to engage the lugs of a wrist watch, a member movably mounted between said side walls and provided with a finger, said body member having a hook at its opposite end, the opening of which is closed by said finger, whereby said finger or said hook may engage the end link of the bracelet to hold it in the selected position of adjustment in said body member.

25 3. A device for connecting a link bracelet to a wrist watch comprising a body member having side walls and means at one end to engage the lugs of a wrist watch, a member movably mounted between said side walls and provided with a plurality of spaced fingers, said body member having a hook at its opposite end, the opening of which is closed by one of said fingers, whereby any one of said fingers or said hook may engage the end link of the bracelet to hold it in the selected position of adjustment in said body member.

40 4. A device for connecting a link bracelet to a wrist watch comprising a body member having side walls and means at one end to engage the lugs of a wrist watch, a member having laterally extending trunnions pivotally mounted in said side walls and provided with a plurality of spaced fingers, said body member having a hook at its opposite end, the opening of which is closed by one of said fingers, whereby any one of said fingers or said hook may engage the end link of the bracelet to hold it in the selected position of adjustment in said body member.

45 5. A device for connecting a link bracelet to a wrist watch comprising a body member having side walls and means at one end to engage the lugs of a wrist watch, a member having laterally extending trunnions pivotally mounted in said side walls, and provided with fingers at both of its ends either one of which may extend into the opening of the

link of a bracelet positioned in the body to adjustably secure it thereto.

6. A device for connecting a link bracelet to a wrist watch comprising a body member having side walls and means at one end to engage the lugs of a wrist watch, a member having laterally extending trunnions pivotally mounted in said side walls, and provided with fingers at both of its ends, either one of which may extend into the opening of the link of a bracelet positioned in the body to adjustably secure it therein.

In testimony whereof I affix my signature.

SYLVESTER A. JOHNSON.
